OVEN CONVEYER

Laurent Rondelin, Bermondsey, England, assignor to Peek Frean & Company Limited, London, England, and Laurent Rondelin, London, England

Application June 27, 1935, Serial No. 28,739
In Great Britain November 29, 1934

7 Claims. (Cl. 107—57)

The manufacture of biscuits, as is well known, involves the use of doughs or mixtures of a variety of kinds which necessitate, or are by choice subjected to, different heat treatments. For example, in some cases biscuits are baked on sheets and in other cases on wires. Where ovens are employed, equipped with endless carriers, on to which sheet metal pans or wire trays can be alternatively placed, it is an easy matter to change from one procedure to another. Where however the biscuits are traversed through an oven directly upon an endless web it is not so easy to substitute one kind of web for another, and therefore there are found in establishments duplicate plants, one equipped with a non-perforated endless metal band and another with an endless skeleton band of wire, neither of which could be expeditiously and quickly brought into use to perform the duty of the other.

According to the present invention a skeleton or wire endless band is combined with a plain or non-perforated endless band or removable support in such a manner that, throughout a heating zone, a run of the skeleton band is immediately above a run of the other band, or the removable support. With either combination the skeleton or wire endless band may be used travelling in contact with its companion band or support, while an oven having a wider range of usefulness than has heretofore been possible for heat treatment of articles or material in different ways, is attainable by the provision of means for separating the skeleton band from the companion band or support.

In the accompanying drawings, Fig. 1 is a diagrammatic view in which the use of two endless bands is contemplated for carrying out the invention. Fig. 2 is a similar view of the same with the bands in another position and Fig. 3 is a plan corresponding to Fig. 2 with part of one of the bands broken away. Figs. 4, 5, 6 and 7 are views of modified arrangements. Fig. 8 is a conventional view of a band and support combination according to the invention.

As shown in Figs. 1, 2 and 3 a wire conveyer band 1 is superimposed on a plain steel conveyer band 2 so that both travel together, the outer wire conveyer band 1 being frictionally driven from the inner conveyer band 2 which is mounted upon suitable operating drums or rollers 3. The upper supporting runs of the two bands 1, 2 may be achieved in any suitable way by any appropriate means, the run of the outer conveyer band 1 being shown in Fig. 2 as raised. A convenient way of doing this is by inserting spacing

means laterally into the oven between the juxtaposed runs. In Figs. 2 and 3 two rods 4 and 5 are shown as employed, but either might be used alone, the positioning or spacing of the rod or rods or equivalent, in the direction of the length of the oven being chosen to determine the distance that the conveyer runs are separated, and, it may be, the point at which separation occurs. Similarly the positioning or dimensioning of the rod, rods or equivalent may be made use of to determine the character or extent of separation of the conveyer runs.

In some cases the top run of the inner conveyer band 2 may be depressed, Fig. 4 exemplifying four rods 4^a, 4^b and 5^a, 5^b as employed for the purpose.

Again, if desired one run may be raised and the other depressed, this being exemplified in Fig. 5 as achieved by two rods 4^c, 5^c of appropriate diameter, appropriately positioned.

If it is necessary to tension the band 2 after removal of any of the rods this may be effected by inserting a jockey roller 2^a as indicated in Fig. 4.

Although in the foregoing examples the two bands are to all intents and purposes equal in length, it is obvious that the wire band 1 may be longer than the other and the upper run allowed to sag so that it can rest upon the other band 2 as shown in Fig. 6 or be separated to a greater or lesser extent therefrom in any suitable way such as by supporting means as in Fig. 2.

Fig. 7 illustrates two bands 1, 2 which may be of different lengths arranged so that the lower run of the band 1 can be brought into contact with, or separated from, the upper run of band 2.

As will be obvious optional separation of an endless skeleton band from a stationary support removable through say the side of an oven will enable the skeleton band to be used in different ways, including use by itself. Such a modification is shown in Fig. 8 where 6 represents two overlapping plates which may be slid into place, beneath a wire band 1, through slots 8 in the sides of the oven 9. In this example the upper run of the band 1 can be raised out of contact with the plates when desired such as by the means shown in Fig. 2.

What I claim is:—

1. In an oven, a skeleton endless conveyer, a non-perforated support in relation to which one run of the skeleton conveyer is in close juxtaposition, and means whereby the said run can be separated from the companion support.
2. An arrangement according to claim 1 in

- which the non-perforated support is an endless band.
3. An arrangement according to claim 1 in which the non-perforated support is stationary.
5. 4. In an oven, a skeleton endless conveyer band, a companion non-perforated supporting band with one run of which a run of the skeleton band travels in contact and means adapted to be applied to separate such normally contacting 10 runs for a predetermined distance when desired.
5. In an oven, a plain steel conveyer band, operating drums upon which such band is mounted, and a wire conveyer band superimposed on the plain band so that both travel together, the outer band being frictionally driven from the inner band, and means adapted to be applied to 15 secure separation between contacting runs of the two bands for a predetermined distance when desired.
10. 6. In an oven, a plain steel conveyer band,

operating drums upon which such band is mounted, a wire conveyer band superimposed on the plain band so that both travel together, the outer band being frictionally driven from the inner band, and means adapted to be applied to 5 secure separation between contacting runs of the two bands for a predetermined distance when desired.

7. In an oven, a plain steel conveyer band, operating drums upon which such band is 10 mounted, a wire conveyer band superimposed on the plain band so that both travel together, the outer band being frictionally driven from the inner band and rods adapted to be inserted laterally between contacting runs of the conveyers to 15 raise one run clear of the other when desired.

LAURENT RONDOLIN.
